UNITED STATES PATENT OFFICE

2,068,171

BREATHING DEVICE

Edward Bell Fishburne, Anniston, Ala.

Application December 16, 1935, Serial No. 54,757

3 Claims. (Cl. 128—145)

My invention is a breathing device which is applied to the nose of the user.

An important object of the invention is to provide a device of the above mentioned character which is applied to the nose of the user, while being shaved, with a hot towel or towels applied to the face, affording communication between the interior of the nose and the atmosphere exteriorly of the hot towels, thereby preventing the 10 inhaling of hot vapors from the towels.

A further object of the invention is to provide a device of the above mentioned character, which is extremely simple in construction, and will be held in place, in use, by the towel.

15 A further object of the invention is to provide a device of the above mentioned character which may be made of paper or cardboard, so that it can be discarded after use.

20 A further object of the invention is to provide a device of the above mentioned character which may be made in different sizes for fitting different sizes and shapes of noses.

25 A further object of the invention is to provide a blank from which the device may be quickly and conveniently assembled, so that such devices may be shipped to the user in the knocked down condition, thus economizing in space.

30 Other objects and advantages of the invention will be apparent during the course of the following description.

In the accompanying drawing forming a part of this application and in which like numerals are employed to designate like parts throughout the same,

35 Figure 1 is a perspective view of a breathing device embodying my invention, showing the same applied to the nose,

Figure 2 is a central longitudinal sectional view through the same, in use,

40 Figure 3 is a perspective view of the device, removed,

Figure 4 is a plan view of a blank from which the device is formed,

45 Figure 5 is a plan view of the overlapping ends of the inner side of the device, showing the attaching means thereof, and,

Figure 6 is a plan view of a blank showing a further form of attaching means.

50 The blank 5 is originally flat and has spaced transverse scored or folding lines 6 and 7, forming an inner side section 8, intermediate side sections 9 and outer side sections 10, all of which are integral, as is obvious. The side sections 8 and 9 have their lower end portions or exten-

sions 11 provided with curved edges 12, as shown. The folding line 6 projects through one end extension 11, while the end extension projects downwardly below the lower end 13 of the adjacent side section 10. Arranged between the 5 extensions 11 is a lip-engaging flap 14, integral with the side section 8 and foldable with relation thereto, upon a scored or folding line 15. The lip-engaging flap 14 is separate from the end extensions 11, as shown. The side sections 10 10 are cut away along the line or edge 16, for producing a nose receiving opening 17.

In forming the breathing device from this blank, the side sections 9 are folded upon the lines 6, transversely of the side section 8, until 15 they assume a position at substantially a right angle to the side section 8, and then the side sections 10 are folded transversely with relation to the side sections 9, upon the folding lines 7 until the side sections 10 are substantially parallel to the side section 8. The reduced ends 10' of the side sections 10 overlap and are secured together by any suitable means, such a cement which will not readily dissolve in hot water vapor. I also contemplate securing these 25 overlapping ends together by means of a mechanical device, such as a staple 11', as shown in Figure 5. I may also equip one end 10' with a transverse slit 12' for receiving a hook 13', formed upon the end 10' of the companion side 30 section 10. I also contemplate assembling the device and shipping the same to the user in the assembled condition with the ends 10' connected by any suitable means.

In use, the assembled device, which is in the 35 nature of a hollow rectangular box or shell, is applied to the nose as indicated in Figures 1 and 2. The end of the nose projects into the shell and through the opening 17, and the shell is arranged generally at a right angle to the 40 longitudinal axis of the nose and projects laterally beyond the nose for a substantial distance. The lip-engaging flap 14 engages the lip and is bent thereby outwardly with respect to the side 8 of the shell, and the towel is folded 45 over this lip-engaging extension so that the shell is held in place upon the nose by the towel. The extensions 11 engage with the face adjacent to the nose and conform generally to the contour of the face or lip at the base of 50 the nose. The nostrils are spaced from the side 8 so that breathing may properly occur and the outer end of the shell is arranged exteriorly of the towel and in free communication with the atmosphere, with the result that proper breath- 55

ing may occur and the hot water vapors will not be drawn into the nostrils.

It is to be understood that the forms of my invention herewith shown and described are to be taken as preferred examples of the same and that various changes in the shape, size and arrangement of parts may be resorted to without departing from the spirit of my invention or the scope of the subjoined claims.

10 Having thus described my invention, what I claim is:

1. A blank for forming a breathing device to be applied to the nose, said blank having pairs of folding lines for dividing the blank into an inner side section, intermediate side sections and outer side sections, the outer side sections being cut away to provide a nose receiving opening, the blank further comprising a lip-engaging flap secured to the inner side section.

15 2. A blank for forming a breathing device, having pairs of folding lines for dividing the blank into an inner side section, intermediate side

sections, and outer side sections, the outer side sections being cut away to provide a nose receiving opening, the blank further comprising spaced extensions at the ends of the inner side section and intermediate side sections, and a 5 lip-engaging flap carried by the inner side section and arranged between the spaced extensions.

10 3. A breathing device to be used with a hot towel or the like applied to the face, said device comprising an elongated shell, said shell having oppositely arranged substantially flat sides, one side having a nose receiving opening formed therein, the opposite side having a flap attached thereto and foldable to engage upon the upper 15 lip, the flap being confined substantially within the limits of the width of its side and being engaged by the towel or the like for holding the device in place, said shell having its opposite ends open.

20 EDWARD BELL FISHBURNE.
